UNITED STATES PATENT OFFICE.

MORRIS BROWN, OF NEW YORK, N. Y.

CIGAR-BOX.

SPECIFICATION forming part of Letters Patent No. 732,919, dated July 7, 1903.

Application filed August 2, 1901. Renewed December 1, 1902. Serial No. 133,458. (No model.)

To all whom it may concern:

Be it known that I, MORRIS BROWN, a citizen of the United States, residing at New York, in the county of New York and State of New

5 York, have invented certain new and useful Improvements in Cigar-Boxes, of which the following is a full and complete specification, such as will enable those skilled in the art to which it appertains to make and use the same.

10 This invention relates to cigar-boxes, and is an improvement on that described and claimed in United States Letters Patent No. 640,741, granted to me January 9, 1900, and the object thereof is to add to the advantages or improvements of the cigar-box described and claimed in said patent automatic devices for canceling or destroying the stamp on the box as the cigars are removed therefrom, and also to render the box described in

15 20 said patent more compact in form and more uniform and symmetrical in shape, and with these and other objects in view the invention consists in a cigar-box constructed as hereinafter described and claimed.

25 The invention is fully disclosed in the following specification, of which the accompanying drawings form a part, in which the separate parts of my improvement are designated by the same reference characters in

30 each of the views, and in which—

Figure 1 is an end view of a cigar-box made according to my invention; Fig. 2, a longitudinal section thereof on the line 2 2 looking toward the front of the box; Fig. 3, a front 35 view of the box and showing a revenue-stamp thereon; and Figs. 4, 5, and 6 are sectional details of the construction.

In the practice of my invention I provide a cigar-box of the usual form and comprising 40 a body portion open at the top and provided with a hinged cover *a*, said body portion being composed of ends *b*, a bottom *c*, a front *d*, and a back *e*. The box is also provided with a false and vertically-movable spring-supported bottom *f*, which fits therein and which is supported by a spring *g* and which is adapted to be depressed close to the main bottom of the box in the operation of filling the box with cigars.

45 50 The front and back sides *d* and *b* of the box are provided at each end with notches or recesses *h*, which are triangular in form, the

bottom walls thereof being horizontal and the back walls inclined upwardly and inwardly, as clearly shown in Fig. 4, and at the top of these notches or recesses are sockets *i*, and the false bottom *f* is provided adjacent to each corner with outwardly-directed spring-operated bolts *j*, which are adapted to enter the notches or recesses *h* and which are forced outwardly by springs *k*, and in the normal operation of this device as the cigars are removed from the box the false bottom is gradually raised, the bolts *j* enter successively the notches or recesses *h* as each tier of cigars is removed from the box, and when the last tier is reached the bolts *j* enter the sockets *i* and the box cannot be refilled with cigars, as the false bottom cannot be depressed. The box is also provided at one end with a vertical 70 opening *l*, behind which is a countersunk plate *m*, having a vertical slot *n*, and said plate is provided at one side of said slot with pivoted indicators *o*, which are normally projected, when the box is filled with cigars, across 75 the slot *n*.

The opening *m* in the end of the box is provided at its sides with rabbet-grooves *p*, in which is placed a glass *r*, through which the indicators *o* may be seen, and the false bottom *f* of the box is provided with a pin *s*, which passes through the slot or opening *n* and is adapted to move the indicators *o* upwardly as the false bottom rises in the box, and by means of the indicators *o*, one of 85 which is employed for each of the layers of cigars in the box, it may be determined at any time how many layers of cigars remain in the box. The mechanism of this part of the construction is substantially the same as 90 that shown and described in the patent referred to; but in this improvement the indicators *o* and the glass *r* are all countersunk and are flush with the end of the box. The false bottom *f* is also provided at the front 95 side thereof and adjacent to one end with a sharp-pointed pin or blade *t*, which projects through a vertical slot *u* in the front of the box and over which in practice the stamp *w* is placed, and as the false bottom in the box rises, as hereinbefore described, the stamp *w* will be destroyed by the blade or pin *t*, and the details of this construction are shown in Fig. 6. It is also necessary to provide means for

holding the false bottom down in the operation of packing the cigars and means whereby the said false bottom will be released after the box has been filled, and for this purpose I 5 connect with the bottom *c* at *x* a loop-shaped or bow-shaped spring *y*, the loop-shaped portion of which bears on the bottom of the false bottom *f*, as shown in Fig. 5, and one side or arm of which is slightly shorter than the 10 other, the shorter arm being passed through a staple or similar device *z*, secured to the bottom of the false bottom *f*, and in practice the false bottom *f* is held down by the spring *y* in the operation of packing the cigars in 15 the box; but in the operation of compressing the cigars when the cover is secured the spring *y* is released from the staple or other device *z*, and when the cover of the box is opened the false bottom *f* will be ready to 20 rise, as hereinbefore described. The tension of the spring *g* is so regulated that the false bottom rises as the successive layers of cigars are removed from the box, and the weight of the cigars is all that holds the false 25 bottom down after the box has been opened or the fastening of the cover thereof broken.

Having fully described my invention, what I claim as new, and desire to secure by Letters Patent, is—

30 1. A cigar-box provided with a vertically-movable spring-operated false bottom, means for preventing the downward movement of said false bottom, and countersunk indicators at one end of the box adapted to be operated by said false bottom as the latter rises so as to indicate the number of tiers or layers of cigars in the box, the front of the box being also provided with a vertical slot and said false bottom with a pointed attachment which 35 passes therethrough, substantially as shown and described.

2. A cigar-box provided with a vertically-movable spring-operated false bottom, the sides of the box being provided at each end 40 with triangular notches or recesses, and said 45

false bottom being provided at each corner with spring-operated bolts adapted to enter said notches or recesses, whereby the said false bottom may be forced upwardly but cannot be depressed, said box being also provided at one side with a slot over which the stamp is placed, and said false bottom with a pointed instrument which passes through said slot and through said stamp, substantially as shown and described. 50

3. A cigar-box provided with a vertically-movable spring-operated false bottom, devices for preventing the depression of said false bottom, said box and said false bottom being also provided with means for destroying the stamp on the box as the false bottom rises, substantially as shown and described. 60

4. A cigar-box provided with a vertically-movable spring-operated false bottom, devices for preventing the depression of said false bottom, countersunk indicators at one end of said box adapted to be operated by the false bottom as it rises so as to indicate the number of tiers or layers of cigars in the box, one side of the box being also provided with a slot over which the stamp is placed, and said bottom being provided with an attachment passing through said slot, substantially as shown and described. 65

5. A cigar-box provided with a vertically-movable spring-operated false bottom, means for preventing the downward movement of said false bottom after it has been raised or partially raised, and devices connected with the bottom and the false bottom for holding 70 said false bottom in its lowermost position, substantially as shown and described. 75

In testimony that I claim the foregoing as my invention I have signed my name, in presence of the subscribing witnesses, this 8th day 80 of February, 1901.

MORRIS BROWN.
